UNITED STATES PATENT OFFICE.

GUY SPRINGER JENKINS, OF NEW YORK, N. Y., ASSIGNOR TO AMERICAN RING COMPANY, OF WATERBURY, CONNECTICUT, A CORPORATION.

DESIGN FOR A MUSTARD-JAR.

47,696.

Specification for Design.

Patented Aug. 10, 1915.

Application filed June 9, 1915. Serial No. 33,193. Term of patent 7 years.

To all whom it may concern:

Be it known that I, GUY SPRINGER JENKINS, a citizen of the United States, residing at New York, in the county of New York and the State of New York, have invented and produced a new, original, and ornamental Design for Mustard-Jars, of which the following is a specification.

The design is shown in the accompanying drawing and in which the figure is a perspective view of a mustard jar showing my new design.

I claim:

The ornamental design for a Mustard Jar as shown.

GUY SPRINGER JENKINS.

Witnesses:

A. W. MELLEN,
Wm. BUETTNER.
